Primary Examiner — Janice Seeger(74) *Attorney, Agent, or Firm* — Saidman DesignLaw Group(57) **CLAIM**

The ornamental design for table base, as shown and described.

DESCRIPTION

The sole FIGURE is a perspective view of a table base showing my new design.

The dashed broken lines illustrate environmental structure and form no part of the claimed design. The relatively thin shade lines represent contour, not surface decoration.

UNITED STATES PATENT AND TRADEMARK OFFICE
CERTIFICATE OF CORRECTION

PATENT NO. : D693,613 S
APPLICATION NO. : 29/424878
DATED : November 19, 2013
INVENTOR(S) : Nicholas Polidoros

Page 1 of 1

It is certified that error appears in the above-identified patent and that said Letters Patent is hereby corrected as shown below:

On the Title Page:

The last paragraph of the description before the claim, which was omitted, should read as follows:

Those portions of the table base not shown in the sole figure form no part of the claimed design.

Signed and Sealed this
Seventh Day of October, 2014

Michelle K. Lee
Deputy Director of the United States Patent and Trademark Office
